UNITED STATES PATENT OFFICE.

JOSEPH RAUWALD, OF MILWAUKEE, WISCONSIN, ASSIGNOR TO KEY SAFE COMPANY, OF MILWAUKEE, WISCONSIN.

SAFE.

1,254,433.

Specification of Letters Patent. Patented Jan. 22, 1918.

Application filed March 6, 1917. Serial No. 152,570.

To all whom it may concern:

Be it known that I, JOSEPH RAUWALD, a citizen of the United States, and resident of Milwaukee, in the county of Milwaukee and 5 State of Wisconsin, have invented certain new and useful Improvements in Safes; and I do hereby declare that the following is a full, clear, and exact description thereof.

The present invention relates to new and 10 useful improvements in safes more particularly of the type adapted for altar tabernacles and disclosed in Patent No. 1,185,539, granted to Joseph Rauwald, John Rauwald, Joseph G. Rauwald, Edmund H. Rauwald 15 and Frank Rauwald, May 30, 1916, and comprising inner and outer casings having independent doors connected for simultaneous opening and closing movements.

It is in general the object of the present 20 invention to simplify and otherwise improve the structure and to increase the efficiency and operation of devices of this character and more particularly with respect to the simultaneous movement of the inner and 25 outer doors, it is an object to provide an arrangement wherein such movement may be procured in an exceedingly positive and easily actuated manner.

A further object resides in the provision 30 of a means for locking the outer doors together which is operable incidental to the opening movement of the doors, by the application of the usual actuating key.

With the above and other objects and advantages in view, the invention resides more particularly in the novel combination, formation and arrangement of parts herein-after described and particularly pointed out in the appended claims.

40 In the drawings:

Figure 1 is a horizontal sectional view through the safe between the top walls of the inner and outer casings, the plane of this section being indicated by the line 1—1 of 45 Fig. 3.

Fig. 2 is a horizontal sectional view between the bottom walls of the casings looking upwardly, as indicated by the line 2—2 of Fig. 3.

50 Fig. 3 is a vertical sectional view through the safe on the line 3—3 of Figs. 1 and 2, the lower portion of this view being cut in a plane inwardly of the upper portion.

Fig. 4 is a vertical transverse sectional view through the safe on line 4—4 of Fig. 55 2, looking outwardly.

Referring by numerals to the drawings, 5 indicates a cast-metal frame constituting the front of an outer all-metal casing, and the frame is provided with rearwardly extending jamb-flanges 6 offset inwardly. Top, bottom and side wall plates 7, 8 and 9 respectively are secured to and extend rearwardly from the peripheral edges of the frame 5 and terminate at a rear wall 10. 60 65

Within the outer casing is a chamber comprising cast-metal top and bottom plates 11 and 12 respectively, and a sheet-metal shell 13 comprising the side and rear walls of the chamber, the plates and chamber being secured together by screws 14 passed through projected ears of the plates and engaged in holding rods 15. The rear portions of the plates and top and bottom walls are braced and secured together by screws 16 passed through the walls 7 and 8 and engaged in bosses 17 projecting outwardly from the plates. The walls of the chamber and of the casing are spaced apart throughout and thus an air space surrounds the entire chamber. 70 75 80

The forward portions of the plates 11 and 12 are secured to corresponding top and bottom outer casing walls 7 and 8 by bosses 18 projecting outwardly from the plates and connected with the said walls and these 85 bosses serve also as the pivots for upper and lower pairs of crank arms 19 and 20 respectively, which carry at their outer ends a pair of arcuate sliding doors 21 adapted to close the space between the jamb-flanges 6 of the 90 casing frame 5, the inner edges of these doors being adapted to overlap, and being provided with inturned vertical flanges 22 adjacent said edges which abut when the doors are closed. The inner ends of the crank- 95

arms 19 comprise circular journal plates 23 and between said plates and the inner chamber plate 11 and also between the upper head 23 and a plate 24 on the upper boss 18 are disposed annular series of ball-bearings 25 100 surrounded by suitable retaining rings 26. The plate 24 is secured on the boss 18 by a screw 27 passed therethrough and threaded in the boss, and the securement of the outer top wall 7 to the boss comprises a screw 28 105 passed through said wall and threaded into

the boss carried screw 27. The inner ends of the crank-arms 20 comprise bearing heads 29 on the lower boss 18 and between these heads and the inner chamber wall 12 and a plate 30, similar to the plate 24 are disposed ball-bearings 31, retained by rings 32, the plate 30 and the bottom outer casing wall 8 being secured by screws 33 and 34, similar to the screws 27 and 28. At the inner sides 10 of the heads 29 are formed arcuate series of gear teeth 35 meshing with a preferably beveled gear pinion 36 carried on a shaft 37 having one end journaled in the lower boss 18 whereby upon rotative movement of the 15 shaft in either direction, the doors 21 will be opened or closed.

For simultaneously rotating this shaft, and actuating a locking means for the doors, a lock casing 38 is carried at the lower central portion of the outer casing frame 5 by 20 securing to said casing and to a dependent ear 39 at the front of the lower chamber plate 12 and rotatively mounted in this casing is a spindle 40 recessed at its outer end 25 to receive a suitably longitudinally grooved key 41. The head of this key being provided with pins 42 adapted to engage in the spindle, whereby upon rotative movement of the spindle by the key, the shank of said 30 key will be relieved from strain. The inner end of the spindle rotatively seats in the enlarged socketed end 43 of the gear-shaft 37 and is limited in its movement with respect thereto by means of a lateral lug 44 35 projecting through a slot 45 in the sleeve.

The limited freedom of movement of the spindle with respect to the sleeve 43 serves to release or actuate a suitable door locking means, a continued movement of the spindle 40 turns the shaft to open or close the doors.

This locking means for the doors comprises a lever 46 pivoted at one end to one of the doors 21 adjacent its inner edge, and having its other end adapted to project 45 through slots 47 in the door flanges 22 and upwardly extending in hook shape whereby when said end is raised the doors are locked together. To the intermediate portion of the lever is pivoted a locking bar 48 slidable 50 through guide lugs 49 on the inner face of the door and having a rounded head at its upper end slotted to receive a depending lug 50 on the upper chamber plate 11. The lever is normally urged to its raised locking 55 position by a spring 51 and carries pad blocks 52 engageable with the guide lugs 49. The locking bar 48 is extended downwardly below the plate 12 at its forward edge and terminates in an inwardly extended finger 60 56 engageable by the lug 44 of the lock spindle.

Taking up now the operation of the doors 21 and locking means, it is seen that when the doors are closed and locked that upon insertion of the key in the lock spindle and

initial movement of said spindle, the locking bar will be depressed to simultaneously release both the locking connections of the doors. Upon completion of this movement, the lug 44 of the spindle will abut the end 70 of the slot 45 and continued movement of the spindle will rotate the shaft 37 to swing the doors open. As the doors move apart, the finger 56 of the bar 48 moves outwardly of the bifurcations of the lug and the locking bar is raised by the spring 51. In closing movement of the door, the upper head of the locking bar and the hook lever have a cam action with respect to the lug 50 and the slots 47 respectively. 80

The front of the inner chamber is closed by doors 57 which are provided at their lower ends with depending pintles 58 journaled in the bottom plate 12 and provided at their inner upper corners with pintles 59 85 journaled in the upper plate 11. At the upper edge of each door adjacent its pivotal axis is provided an upstanding pintle 60 slidable in an arcuate slot 61 in the plate 11. Journaled on one of these pintles is a roller 90 62 and the other of said pintles has secured thereto one end of a bar 63 which has its intermediate portion secured to the projected end of the adjacent pivot pintle 59 and which is extended rearwardly of said pintle 95 for securing to one end of a link 64 which is secured at its other end to the roller carrying pintle 62. Secured to one of the upper outer door crank-arms 19 is a forwardly projecting cam-block 65 adapted to engage 100 the roller 62 to swing the inner doors to closing position, and extending from this cam-block under the arm 19 is a retaining wall 66 against which the roller 62 abuts to positively lock the inner doors in closed position when the outer doors are closed or partially closed. Opening movement of the inner doors is effected by abutment of one of the flanges 22 of the outer doors with a lateral wing 67 at the inner end of the corresponding inner door. 105

What is claimed is:

1. A structure of the class described including a casing, a door for closing the casing, means for locking said door, means for moving said door including members having limited relative movement, and means connecting one of said members and the locking means for releasing said locking means upon relative movement of the said member with respect to the other member. 115

2. A structure of the class described including a casing, a door for closing the casing, means carried by and movable with the door for locking it, said locking means including a portion movable relatively with respect to the door, means for moving said door, and said door moving means being engageable with the door locking means in the closing position of said door. 125

3. A structure of the class described including a casing, a door for closing the casing, means for moving the door including a shaft and a lock spindle connected therewith 5 in a manner permitting limited relative pivotal movement, means for locking the door and said means being operable by the lock spindle during its limited movement relative to the shaft. 10 4. A structure of the class described including a casing, a door for closing the casing, means for moving the door including a shaft and a lock spindle connected therewith in a manner permitting limited relative pivotal movement, means carried by and movable with the door for locking it and including a slideable bar, and a lateral extension on the spindle detachably engageable with the slideable bar in the closing position of the 15 door. 20 5. A structure of the class described including a casing, a pair of doors for closing the casing, an apertured inturned extension at the inner edge of one door, a hook member detachably engageable through said extension and secured to the other door, an operating bar connected with said hook member, means for moving said doors including a shaft and a lock operating member connected therewith in a manner permitting limited relative movement, and said lock operating member being engageable with the 25 said operating bar, in the closing position of said doors. 30 35 6. A structure of the class described including a casing, a door for closing the casing, means for moving the door including a shaft, having a socketed end provided with a transversely extended slot, a lock spindle engaged in the socketed end, and a lateral extension on the spindle engaged in the slot, means for locking the door, and said means being engageable by the lateral extension of the spindle. 40 45 7. A structure of the class described including a casing, doors for closing the casing, pivotal carrying arms secured to the doors and having their pivot ends provided with gear-segments, a shaft, a pinion on the shaft meshing with said segments, a lock-cylinder including a spindle connecting with the shaft in a manner permitting limited sliding movement, means for locking the doors, and said means being operable by the 50 55 spindle during its limited sliding movement with respect to the shaft. 8. A structure of the class described, in- cluding a casing, a pair of doors for closing the casing, an apertured inturned extension at the inner edge of one door, a hook member detachably engageable through said apertured extension and secured to the other door, an operating bar connected with said hook member, means for moving said doors, and means connected with the last mentioned means for actuating said operating bar when said first mentioned means is operated. 60 65 9. A structure of the class described including a casing, a chamber therein, a door for closing the casing, pivoted doors for closing the chamber, a link connecting said chamber doors at opposite sides of their pivots and means carried by the casing door for actuating one of the chamber doors. 70 10. A structure of the class described, including a casing, a chamber therein, a door for closing the casing, and movable in an arcuate path, pivoted doors for closing said chamber, means connecting the chamber doors for procuring simultaneous actuation 80 thereof, a projection on one of the chamber doors, and a closing cam movable with the casing door and engageable with the said projection. 85 11. A structure of the class described, including a casing, a chamber therein, a door for closing the casing, and movable in an arcuate path, pivoted doors for closing said chamber, means connecting the chamber doors for procuring simultaneous actuation 90 thereof, a projection on one of the chamber doors, a closing cam movable with the casing door and engageable with the said projection, and a retaining flange movable with the casing door and adapted for engagement 95 with the said projection of the chamber door and curved to correspond to the curved path of movement of the casing door. 12. A structure of the class described including a casing, a chamber therein, a door for closing the casing, pivoted doors for closing the chamber, a link connecting said chamber doors to procure simultaneous actuation thereof, a projection on one of the chamber doors, and a coöperating projection 100 on the casing door to engage the first mentioned projection when moved to an open position to similarly actuate said chamber doors. 105

In testimony that I claim the foregoing I have hereunto set my hand at Milwaukee, in the county of Milwaukee and State of Wisconsin.

JOSEPH RAUWALD.
